BUTTON LOOP

John H. Domkee, West Haven, Conn., assignor
to The Wire Novelty Manufacturing Company,
West Haven, Conn., a corporation of Connect-
icut

Application July 25, 1932, Serial No. 624,375

1 Claim. (Cl. 24—73)

This invention relates to improvements in button loops and more particularly to that class of button loops known as the rigid type having substantially no resiliency and therefore provided with a rigid restricted throat portion connecting the button-receiving loop with the button-retaining loop and permitting the shank of a button inserted in the receiving loop to slide through the throat portion and into the retaining loop. The rigid type of button loops, previous to this improvement, provides a structure having a suspension loop, a button-receiving loop and a button-retaining loop, the two last mentioned loops having an intermediate restricted throat portion substantially inexpandable and therefore providing a fixed passage through which a button-shank of the greatest diameter may pass upon entering or leaving the retaining loop. The ease with which a button may be released unintentionally from the retaining loop of the rigid type of button loops has led to a preferred use of the resilient type of button loops which provides for the expansion of the throat portion of such loop to enable a button-shank of a diameter greater than that of the normally contracted throat portion, to pass therethrough and become seated within the retaining loop and there held against release therefrom excepting as it may again expand the throat portion against the inherent resiliency of the wire of which the button loop is chiefly made. Besides the wire structure of such resilient button loops there is invariably employed a connecting member of sheet metal within which the ends of the wire button loop structure are held for relative movement upon the expansion and contraction of the throat portion.

The improved button loop, about to be described, makes possible the use of a single-piece wire rigid button loop having all of the advantages of the resilient type of button loop and capable of being manufactured at a cost less than that of the previous rigid type; for considerably less wire per unit is required therefor.

The objects of the improvement therefore are to provide a rigid button loop having but one loop within which a button both may be received and held; to provide such a rigid button loop with a suspension loop having a cross-bar a middle portion of which is outwardly off-set to enlarge the suspension loop and thus leave bar extremities for marginal engagement within a loop of a folded strap from which the button loop is suspended; and to provide a rigid button loop, as aforesaid, in which the folded portion of the looped strap, intermediate its marginally en-

gaged portions, provides a yielding portion behind an inserted and seated button within the holding loop to thereby cooperate with the holding loop to secure the inserted button against unintentional release. With these and other objects in view, as may hereinafter appear, the improvement as illustrated is subject to such changes and modifications as may come within the scope of what hereinafter may be claimed.

The character of the improvement may be best understood by reference to illustrative forms of device embodying the invention and illustrated by the accompanying drawing in which the Figure 1 is an upright elevation of the improved button loop with a button inserted therein, the button loop being suspended from a folded strap portion, portions of the strap and the button loop being illustrated in dotted lines; the Figure 2 is a side elevation of the improvement as illustrated by the previous figure, excepting that the button is illustrated as being attached to a member thereby supported; the Figure 3 is an upright elevation of the improvement as illustrated by the first figure, excepting that the button is being tipped against the yielding portion of the strap preparatory to the release of the button from within the button loop; and the Figure 4 is an upright elevation of the button loop, the Figure 5 being a similar elevation of the button loop stamped out from sheet material.

Referring more particularly to the drawing, the improved button loop, while preferably illustrated as made of wire, may be made of other forms of material such as, for instance, sheet metal. The improved button loop is of simple construction, comprising, as it does, the centrally arranged button holding loop 1, the horizontally extending suspension loop 2 and the enlargement 3 of the loop 2. The structure, preferably of wire, may be made in any manner that will provide said loops 1 and 2 and the enlargement 3, but as illustrated a middle portion of a single piece of wire is curvingly bent to form the centrally arranged button holding loop 1 providing the seat 4 for the shank 5 of a button 6, then from both sides of the upper portion of the holding loop 1 the wire end portions are horizontally bent in opposite directions, and one away from the other, to provide the lower bar portions 7 and 8 of the suspension loop 2, and then, at 100 places equidistant from the holding loop 1, both wire end portions are bent upwardly and then backwardly, one toward the other, to provide the upper bar portions 9 and 10 of the suspension loop 2, the wire extremities 11 and 12 then being 110

outwardly off-set in a plane parallel to that of the bar portions 9 and 10, and the faces of the wire stock there made to abut, the engaging metal surfaces of said faces being united in 5 permanent intimate union, as at 13, by means of welding, brazing or soldering, the structure in its welded form providing a compact and rigid unit which, with the cooperation of a strap 14, is adapted to receive, hold and retain a button 6

10 against unintentional release.

The strap 14 is inserted within the suspension loop 2 and then folded back upon itself to provide the strap loop 15 from which the improved button loop is suspended by means of the marginal engagement of the strap loop 15 by the upper bar portions 9 and 10, an intermediate portion 16 of the fold of the strap loop 15, not being immediately reinforced by any bar portion in alignment with the upper bar portions 9 and 10, 15 remaining sufficiently flexible to yield under the application of force, but to normally provide a sufficient barrier behind an inserted button 6 to prevent the unintentional release of the button 6 from within the holding loop 1, as illustrated by 20 the Figures 1 and 2.

In use, the button 6 to be inserted within the button loop is tipped relative to the button loop so that the back of the lower portion of the button 6 may engage a front upper portion of the holding loop 1 to provide a fulcrum by which the upper portion of the button 6 may be forced by the flexible portion 16 of the fold of the strap loop 15, the flexible portion 16 yielding to permit the upper portion of the button 6 to pass 30 through the enlargement 3 as the button slips into the holding loop 1. The button 6 being fully inserted, the shank 5 seats itself into the shank seat 4 and then the button 6 readily assumes an upright position in a plane substantially parallel 35 to the plane of the button loop, thus permitting the flexible portion 16 of the fold of the strap loop 15 to straighten out behind the button 6 and there provide a barrier against accidental removal of the button 6, the flexible portion 16 of the fold of the strap loop 15 cooperating with 40 the holding loop 1 to secure the button 6 within the improved button loop against unintentional release.

To release the button 6 from within the im- 50

proved button loop, the button 6 is tipped so that its upper portion forcibly engages the flexible portion 16 of the fold of the strap loop 15 thereby made to sufficiently yield, as illustrated by the Figure 3, to permit the button 6 to slide out of the holding loop 1. In other words, the passing of the button 6 into and out of the improved button loop requires that a top portion of the button 6 extends into the enlargement 3 which is covered and normally filled out by the flexible portion 16 of the fold of the strap loop 15. Therefore, to enter or withdraw the button 6 into or from the improved button loop, it is necessary that the flexible portion 16 sufficiently yields, that is to be capable of being crowded into and adjacent the upper portion of the enlargement 3 to permit the button 6 to extend into, and thus pass through, the enlarged interior of the button loop.

The Figure 5 illustrates an improved button loop stamped out of sheet material. Like the preferred wire loop, the sheet material loop provides the button holding loop 1', the suspension loop 2', the enlargement 3', the lower bar portions 7' and 8', the upper bar portions 9' and 10', and the seat 4'.

The button loop structure in its wire, or sheet material form, further may be described as a one piece structure providing a horizontally extending loop 2 having opposed enlargements 1 and 3 intermediate its length, the enlargement 1, of course, providing the button holding loop, while the enlargement 3 provides the necessary head room for the button 6 in entering and leaving the button loop.

I claim:—

A rigid button loop comprising a single piece of wire of which a middle portion is curvingly bent to provide a button holding loop, the wire end portions being bent therefrom horizontally outward and then bent back upon themselves to extend horizontally inward to provide a suspension loop above and adjacent to the holding loop, the wire extremities being upwardly off-set and made to abut to provide the suspension loop with an intermediate enlargement, the engaging metal surfaces of the abutting wire ends being united in permanent intimate union.
